ELECTRICALLY OPERATED PUMP

Raymond Leslie Kent and John Neville Morris,
Adderley Park, Birmingham, EnglandApplication July 24, 1933, Serial No. 681,998
In Great Britain October 19, 1932

3 Claims. (CL 175—344)

This invention has for its object to provide an improved electrically operated pump adapted more particularly for supplying petrol or the like to the carburettor of an internal combustion engine.

The invention comprises the combination with the core and hollow cylindrical pole piece of an electromagnet, of an armature in the form of an iron disc, and radially disposed means abutting 10 at their opposite ends against the cylindrical pole piece and armature for holding the latter in its central position during its movement under the action of the magnetic flux.

Also the invention comprises an armature disc 15 formed with a central cavity at the part which co-operates with the adjacent end of the magnet core, the cylindrical pole piece being formed with an annular step for co-operating with the periphery of the disc.

20 Further the invention comprises a pump having the combination and arrangement of parts hereinafter described.

In the accompanying sheet of explanatory drawing:—

25 Figure 1 is a longitudinal section of a petrol pump constructed in accordance with this invention and adapted for use on a motor vehicle.

Figure 2 is a cross section on the line 1—2 Figure 1, and Figure 3 is a cross section on the 30 line 3—4 Figure 1.

In the construction of a petrol pump as shown, we employ an electromagnet the winding *a* of which is carried on a hollow iron core *b*, and is surrounded by a cylindrical iron pole piece *c*. At 35 the open end of the pole piece is arranged an armature *d* in the form of a disc which will be described more fully later. On the closed end *e* of the cylindrical pole piece is carried a contact breaker of any convenient form, consisting in 40 part of a toggle mechanism for producing quick action of the movable contact member. In the example illustrated the said mechanism comprises a pair of levers. One of the levers comprises a pair of rigidly interconnected side members *f*, *f*, and the other comprises a pair of rigidly interconnected side members *g*, *g*, situated between the members *f*, *f*. The two levers are pivoted at one end at *h*, and at their other ends are interconnected by a coil spring *i*. The lever 45 formed by the parts *f*, *f* carries a contact piece *j* which can co-operate with another contact piece *k* carried on a resilient blade *l*. The contact pieces, *j*, *k*, control the electric circuit containing the winding *a* of the electromagnet in the usual way.

50 55 The lever formed by the parts *g*, *g* is connected

to and actuated by a rod *m* which passes through the core *b* and is secured to the armature *d*. In the position shown in Figure 1 the parts *j*, *k* are in contact and the circuit is closed. When by means of the rod *m* the parts *g* are moved to the left, the first effect is to strain the spring *i*. When the parts *g* reach the other side of the parts *f* the latter are moved to the right by the said spring and the contacts *j*, *k* are thereby separated and the circuit is opened. When the rod *m* moves to the right, the parts *g* again move relatively to the parts *f* causing the spring to be strained, until a certain position is passed, and then the spring returns the parts *f* to the initial position causing the circuit to be re-closed. The contact breaker 15 may be enclosed by any convenient cover *n*.

At the open end of the cylindrical pole piece *c* is provided a flange *o* on which is carried a hollow member *p* containing the inlet valve *q* and the outlet valve *r*. One side of this member *p* is 20 shaped to form a shallow pump chamber *s*. The chamber *s* is bounded on one side by the wall *t*, and at the other side it is bounded by a flexible diaphragm *u* which separates the armature disc *d* from the pump chamber. The diaphragm is 25 made from any convenient impervious flexible thin material, and is secured to the armature disc by a plate 13 on the rod *m*. On the opposite side of the wall *t* to the pump chamber, there is formed in the hollow body *p* a chamber *v* which is closed 30 by a removable cover *w*. Petrol is admitted to the chamber *v* through an inlet connection *x*, and before it can gain access to the inlet valve *q* it must pass through the filter *y*. After passing the inlet valve, which is held on its seating by a spring 35 *z*, the petrol can flow through an aperture 2 in the wall *t* to the pump chamber. From the pump chamber the petrol passes again through the aperture 2, and thence through the outlet valve *r*, to the outlet connection 3. Dislodgment of the valve 40 *r* by excessive movement is prevented by a spring ring 4 secured to the part 5 which carries the valve *r*.

In order to obtain as uniform a pull as possible on the armature *d* when the magnet is excited, we form an annular step or shoulder 7 around the interior of the open end of the cylindrical pole piece *c* so as to concentrate the flux in the adjacent edge of the armature, and at the centre of the armature a shallow recess 8 is 50 formed to receive the adjacent end of the core *b*. At first the flux is concentrated in the gaps formed by the outer edge of the armature and the shoulder on the surrounding pole piece, and 55 by the edge of the core and the edge of the re-

cess in the armature. Later the armature passes over the end of the core and finally the pull is exerted mainly by the flux in the gap between the flat end of the core and the base of the afore-said recess. By so shaping the parts we are able to avoid the usual large increase in pull which accompanies reduction of air gap, and obtain a sufficiently uniform pull throughout the movement of the armature.

10 The suction stroke of the pump is effected by the movement of the armature under the influence of the magnetic pull, and this movement is effected quickly. As soon as this stroke is completed the contact breaker is actuated for opening the magnet circuit, and the delivery stroke is effected by a spring 9 situated on the magnet side of the armature. At the end of the delivery stroke the contact breaker closes, and the cycle of operations is repeated.

15

20 Due to the fact that the air gap between the periphery of the armature *d* and the cylindrical pole piece *c* is small, a slight inaccuracy in the centering of the armature results in a strong side pull which may interfere with the proper action

25 of the pump. To neutralize this condition we arrange between a shoulder 10 at the pump side of the armature and a shoulder 11 in the surrounding pole piece a plurality of radial thrust pieces. These may conveniently take the form

30 of discs or thin rollers 12 having spherical peripheries so that each can rock about its points of contact with the armature and outer pole piece. The roller-form of these thrust pieces is convenient because of ease and simplicity of manufacture, but if desired they may consist of quadrilateral pieces having straight sides and curved ends. In the position of the armature shown in Figure 1 the thrust pieces are slightly

35 inclined to the plane of the armature, and they assume a position more nearly corresponding to

the plane of the armature as the latter moves to the left, so that they exert a toggle like action which effectually prevents lateral displacement of the armature.

By this invention we are able to provide an inexpensive and reliable pump suitable for use as a fuel pump or for like purposes in a very simple and convenient manner. The invention is not limited to the example described as subordinate details can be varied to suit different require- 10

Having thus described our invention what we claim as new and desire to secure by Letters Patent is:-

1. In an electromagnetic motor, the combination with the core and hollow cylindrical pole piece of an electromagnet, of an armature in the form of an iron disc, and radially disposed means abutting at their opposite ends against the cylindrical pole piece and armature for holding the latter in its central position during its movement under the action of the magnetic flux, substantially as described. 15

2. In an electromagnetic motor, the combination of an electromagnet core, a hollow cylindrical pole surrounding the core, an armature disc co-operating with one end of the said core and pole piece, a shoulder on each of the disc and pole piece, and roller like abutment pieces situated between the said shoulders, the abutment pieces being arranged and adapted to operate substantially as described. 25

3. An electromagnetic motor as in claim 1, in which the disc is formed with a central cavity at the part which co-operates with the core, whilst the cylindrical pole piece is formed with an annular step for co-operating with the periphery of the disc, substantially as described. 30
